UNITED STATES PATENT OFFICE.

EDMUND SCHROEDTER, OF BROOKLYN, NEW YORK.

IGNITION-VALVE.

1,287,460.

Specification of Letters Patent. Patented Dec. 10, 1918.

Application filed September 10, 1918. Serial No. 253,376.

To all whom it may concern:

Be it known that I, EDMUND SCHROEDTER, a citizen of the United States of America, residing at Brooklyn, New York, have invented 5 a new and useful Ignition-Valve, of which the following is a specification.

My present invention is an ignition valve for gas engines.

The objects of my invention have been to 10 provide simple and effective means for automatically igniting the charge at the proper time.

Briefly stated, the invention resides in the provision of an ignition tube on the exhaust valve arranged to take up an amount 15 of heat from the exhaust gases sufficient to provide for ignition of the fresh charges in the combustion chamber.

A special object of the invention has been 20 to secure sufficient heating of the ignition tube to insure proper ignition of the charge at all times, and especially at the lower engine speeds, when the heat to be derived from the exhaust gases is lesser than at the 25 higher engine speeds.

This latter object I have accomplished in part by locating a portion of the ignition tube transversely of the path of the exhaust gases so as to be entirely surrounded and 30 fully heated thereby.

Other features of the invention will appear as the specification proceeds.

In the accompanying drawing, I have illustrated the invention embodied in one 35 of its practical forms, but as this disclosure is principally for illustrative purposes, it will be understood that various changes and modifications may be made without departure from the true spirit and scope of the invention.

In said drawing:

Figure 1 is a cross sectional view of an engine cylinder having an exhaust valve constructed in accordance with and embodying 45 features of this invention.

Fig. 2 is a plan view of said valve.

Fig. 3 is a cross sectional view of the same taken substantially on the plane of line 3—3 of Fig. 1.

Referring to the drawing now in detail, 5 designates an engine cylinder having a piston 6 working therein, the combustion chamber of said cylinder being designated 7, and the exhaust port or passage being designated 8.

The valve shown is of the puppet type embodying a head 9 and a stem 10, said valve fitting a coöperating conical valve seat 11.

The ignition tube consists in the present 60 disclosure of an annular section or ring 12 of tubing having a plurality of branches 13 opening up through the top of the valve. In the case illustrated, there are three such branches providing openings from the tube 65 up through the valve at three different points. These branches or outlets are preferably distributed at equal distances apart so as to firmly support the lateral portion of the tube.

The tube, including the outlet or firing portions 13 and the laterally extending heating portion 12 may be made in one piece, but at the present time I find it easiest to make the lateral heating portion 12 as a 75 complete ring and to join the branches 13 thereto as by means of the T-shaped couplings 14 which may be stamped to shape from sheet metal and then welded or otherwise secured in position about the ring 80 and the end portions of the tube sections 13.

The ignition tube is made of a material which will withstand the intense heat to which it is subjected. At the present time I find pure nickel tubing the material best 85 suited to this purpose.

The operation it is believed will be readily understood from the foregoing, it being apparent that as the exhaust valve opens the hot exhaust gases escaping past the conical 90 valve seat and the adjoining conical faces of the valve will converge upon the lateral or heating portion of the hot tube which is disposed directly across and transversely of such flow. This brings the tube to a high 95 degree of heat, and entirely surrounded as it is by the exhaust gases the tube is kept hot enough for ignition purposes even when the engine is running slowly. As the tube has a plurality of firing outlets, the charge will be 100 ignited from a plurality of points and hence very rapid flame propagation is secured. Also, if one of the firing tubes should for any reason fail to ignite the charge, ignition is still insured by the presence of the other 105 tube elements. The tube is ordinarily maintained so hot as to prevent carbonization, but if there is any tendency to carbonize, this is ordinarily overcome by the sweeping action of the gases through the tube, it being 110

evident that the plural number of outlets enables a complete flow of gas into and out of the ignition tube.

A point of particular advantage of this construction is that the firing tube can be made in compact form and yet have a considerable heating surface, this being due to the lateral disposition of the dependent portion of the tube and to the fact that such portion is disposed directly across the path of the hot gases. A further advantage is that this construction is adapted for engines where the exhaust passage is relatively shallow, as in the case illustrated, where there would not be room for a long dependent tube. In the illustration I have shown how this form of ignition tube may be employed even in constructions where the valve stem guide comes up very close to the bottom of the valve head. In such illustration the guide, which is designated 15, comes up nearly to the bottom of the valve and the ring portion of the hot tube practically surrounds this guide, that is when the valve is seated.

I claim:

1. In a gas engine valve, a valve head and an igniter tube supported beneath said valve head and opening up through the top of the valve head at a plurality of points.
2. In a gas engine valve, a valve head, an igniter tube supported beneath the valve head, and a plurality of branches from said tube extending up through the top of the valve head.
3. A gas engine valve comprising a valve stem and a head supported thereby, a ring disposed about the valve stem beneath the head, and a plurality of branches extending from said ring up through the top of the valve head.
4. A gas engine valve comprising a valve

stem and a head carried thereby, an igniter tube in the form of a ring encircling the valve stem beneath the head and connected at a plurality of points with the valve head by tubular branches open to the top of the valve head.

5. A gas engine valve comprising a valve stem and a head carried thereby, tubular ignition elements connected with the valve head and open to the upper side thereof, and a tubular portion beneath the valve head connecting the tubular elements aforesaid.

6. A gas engine valve comprising a valve stem and a head carried thereby, and an igniter tube secured to the valve head having its interior open to the top of the valve and having a dependent portion extending substantially laterally beneath the valve head and thereby positioned substantially transversely of the flow of gas past the valve.

7. In combination, an exhaust valve and a coöperating conical valve seat arranged to direct the exhaust gases on convergent lines, and an igniter tube carried by said valve and having a substantially laterally extending heating portion disposed substantially transversely of said convergent flow of exhaust gases.

8. In a gas engine, an exhaust valve and a coöperating conical valve seat engaged thereby, and an igniter tube carried by said valve and having an annular heating portion disposed in the direct path of the exhaust gases traversing the conical valve seat.

9. A gas engine exhaust valve comprising a valve stem, a head carried thereby and an igniter consisting of a tubular ring substantially surrounding the stem beneath the head and having its interior open to the top of the valve.

EDMUND SCHROEDTER.
